COMPUTING MECHANISM

Victor H. Rausch, Maplewood, N. J., assignor to
 John Wood Manufacturing Company, Inc.,
 Conshohocken, Pa., a corporation of Delaware

Application October 17, 1934, Serial No. 748,596

8 Claims. (Cl. 74—111)

My invention may be used as an accessory to metering pumps for dispensing gasoline. The current price of gasoline varies in tenths of a cent, and such pumps have means, including gearing, connected with the meter, whereby as a consequence of movement of the gearing by dispensation of the liquid through the meter, the value of that dispensed liquid, at the current price, is computed and indicated by suitable registering mechanism, conveniently including rotary dials. My invention is particularly applicable to such metering pumps wherein the value based upon the whole cents of the price and the value based upon any fraction of a cent of the price are separately automatically computed by different mechanisms, and my invention includes means whereby the computation of the two mechanisms is aggregated automatically in the registration of the value of the volume dispensed.

As hereinafter described, my invention includes a ratchet wheel, conveniently having one hundred teeth, each representing a tenth of a cent, arranged to be turned by a pawl carrier which is actuated by gearing connection with the means for computing the value based upon the whole cents of the price; and said ratchet is adapted to be advanced in its rotation, with respect to the pawl carrier by connection with the means for computing the value based upon any fraction of a cent of the price so that the aggregate advance movement of said ratchet for each gallon dispensed is in correspondence with the whole price of the gallon including both the whole cents of the price and any fraction of a cent of the price. Said ratchet wheel has in coaxial relation therewith a gear pinion for actuating a registering mechanism of any suitable form or construction for indicating such aggregate value in dollars, cents, and tenths of a cent.

The essential feature of my invention is that the teeth on the ratchet are helically inclined with respect to the axis of its rotation so that said ratchet may be advanced by relative axial movement of said ratchet and a pawl which has its end for engaging the ratchet teeth inclined with respect to the axis of the ratchet, in accordance with the inclination of the ratchet teeth; so that such relative movement is effected by sliding engagement of the pawl and ratchet in the direction of the axial length of said teeth, with the minimum wear upon the ratchet teeth and pawl.

My invention includes the various novel features of construction and arrangement hereinabove more definitely specified.

In said drawings, Fig. I is a fragmentary plan view of a computing mechanism including an embodiment of my invention.

Fig. II is an elevation of said mechanism as seen from the lower side of Fig. I.

Fig. III is a longitudinal sectional view of said mechanism taken on the line III, III in Fig. I in the direction of the arrows on said line.

Fig. IV is a transverse vertical sectional view taken on the line IV, IV in Figs. I and II.

Fig. V is a detail view of the single advancing pawl which is pivoted in the pawl carrier shown in the preceding figures and functions to impart movement from the pawl carrier to the ratchet wheel, in accordance with the whole cents value of the liquid dispensed, and also any additional advance movement in accordance with any fractional cent value per unit of volume of the liquid dispensed.

Fig. VI is a detail view of the axially movable keeper pawl, shown in Fig. I, which is also pivoted in the pawl carrier and functions to prevent backward movement of the ratchet wheel with respect to said pawl carrier.

Fig. VII shows a modified form of my invention differing from that of the preceding figures in that the keeper pawl is not axially movable in the pawl carrier; including a plane development of the toothed circumference of the ratchet and the respective relative position of the two pawls with respect to teeth of said ratchet wheel.

Fig. VIII is a view similar to Fig. VII but showing a different form of keeper pawl.

Fig. IX is a transverse vertical sectional view taken on the line IX in Fig. II in the direction of the arrow on said line, showing the cam which is selectively engaged to operate the knocker mechanism shown in Fig. II.

In said figures, the tubular shaft 1 is conveniently provided with the bevel gear 2 for connection with the metering mechanism so that said shaft is turned one revolution for each gallon of liquid passed through the meter, for dispensation. Said shaft 1 carries the gear 3 engaging the gear 4, of the same size, on the shaft 5 which is journaled in the housing including the vertical partition wall 7. Said gear 4 and shaft 5 are rigidly connected with a series of gears of different sizes, including gears 8, 9, and 10, which represent whole cents of the price of the liquid to be dispensed per gallon, for instance the gear 8 may represent thirty-five cents per gallon; the selected gear 9 thirty cents per gallon; and the gear 10 twenty-seven cents per gallon. Any one of said gears 8 etc. may be manually selectively

engaged with the connecting gear 12 which is mounted in the axially movable carriage 13. Said carriage 13 is supported by the long pinion 14 and holds the gear 12 continually in engagement with said pinion so that motion of any selected one of the gears 8 etc. on said shaft 5 is transmitted to said pinion to turn the latter more or less in accordance with the price of the liquid dispensed.

10 Said long pinion 14 has, rigidly connected therewith by the pin 15, the pawl head 16 having the advancing pawl 17 pivoted therein on the pin 18 and inwardly pressed by the spring 19 into engagement with the toothed face of the ratchet wheel 21 so that whatever rotary movement is imparted to the pinion 14 by the selected cents gear 9 is thus transmitted to said ratchet wheel 21.

Said ratchet wheel is rigidly connected with 20 the sleeve 22 which is axially movable on the shaft 23 which is journaled in the end of said pinion 14 and in the bearing 24 in the housing wall plate 25. Said sleeve 22 is connected by the key 28 so as to turn said shaft 23, and the latter 25 is cut to form the gear pinion 29 continually engaged with the gear 30 leading to any suitable registering mechanism indicating the value of the liquid dispensed.

Said shaft 1, turned as above described one 30 revolution for each gallon of liquid dispensed, also carries a series of nine cams which have respectively different numbers of notches corresponding with the different numbers of tenths of a cent from ".1" to ".9". For instance, the cam 31 has one notch 31'; the cam 32 has three notches 32'; and the cam 33 has nine notches 33'.

The lever 35 is fulcrumed on the screw shaft 36 which is journaled for rotation in said housing plates 7 and 25 but prevented from axial movement therein so that when said lever is lifted from the group of cams, it may be shifted to cooperative relation with any selected one of the cams by turning said screw, conveniently by the milled knob 36'. Said lever 35 being in cooperative 45 relation with the cam 32 representing three tenths of a cent, will be successively raised from the three notches 32' in said cam by each rotation of said cam representing a gallon of liquid dispensed, and its function is to add three tenths 50 of a cent to the computation movement of said ratchet 21 which is effected by the whole cents price gear 9 aforesaid. Said lever 35 is in cooperative relation with the knocker plate 37 which is in fact a U-shaped lever having its bifurcations fulcrumed on said screw shaft 36 so that said plate 37 is uplifted by said lever 35 when the latter is shifted to cooperative relation with any of the series of nine cams.

Said knocker plate 37 is continually in cooperative 60 relation with the short arm of the knocker lever 39 which is fulcrumed at 40 upon the bracket 41 projecting from said housing plate 7, as indicated in Fig. II. The long arm of said lever 39 is bifurcated as indicated in Fig. I, and 65 its free ends bear upon the thrust bearing ring 42 for the balls 42'; which ring is free to turn and slide axially on said sleeve 22 under stress of the knocker spring 44, to advance the value computer ratchet 21 one-tenth cent whenever said 70 lever 35 rises from a cam notch. Said ratchet 21 has one hundred teeth and each upward movement of the knocker lever 39 advances that ratchet to the extent of one tooth. Such advance is effected by said advancing pawl 17 because the 75 teeth of said ratchet 21 are helically inclined, as

indicated in Fig. I, and the edge of said pawl 17 engaging them similarly inclined, to such a degree, (conveniently twenty-five degrees,) that the axial movement of said ratchet relatively to the pawl 17 held axially stationary in said pawl 5 head 16 turns said ratchet slightly more than the angular extent of one tooth, i. e., slightly more one-hundredth of a revolution of said ratchet wheel; the slight excess being merely to permit the keeper pawl 45 to drop into the next 10 tooth on said ratchet to prevent accidental backward turning of the latter.

In the form of my invention shown in Figs. I and II, I find it convenient to pivot said pawl 45 on the pin 46 which is stationary in said pawl 15 carrier 16, and to provide the pawl 45 with the slide bearing 47 which is loosely journaled on said pin 46 but engaged with the axially opposite faces of said ratchet wheel 21 so that as the latter is thrust axially by the movement of said knocker 20 lever 39, said keeper pawl 45 is carried axially with the ratchet. As rotation of said cam shaft 1 permits the lever 35 to drop into the next succeeding notch 32' in the cam 32, said ratchet wheel 21 is returned to the axial position shown 25 in Fig. III and the knocker mechanism is restored to the position shown in Fig. III by said spring 44; such return movement being limited by the stop ring 48 secured at the open end of said pawl head 16 by the screws 49. During such 30 movement the toothed face of the ratchet 21 slides axially with respect to the advancing pawl 17, lifting the inclined edge of the latter over the next tooth in the ratchet so that it is dropped into engagement with that tooth, preparatory to 35 the next advancing movement of the ratchet.

However, the construction shown in Figs. I and II may be simplified, as indicated in Fig. VII, by omitting the pawl slide bearing 47 and substituting an axially longer, but axially immovable keeper pawl 45' for the axially movable keeper pawl 45 shown in those figures. In Fig. VII, the advancing pawl 17 and the modified keeper pawl 45' are conveniently shown in closer relation upon the plane development of the toothed face of the ratchet 45 21 than they are in fact in the actual mechanism. It may be observed that whereas the advancing pawl is in close engagement with the tooth of the ratchet which it is to advance; the keeper pawl 45' is in slightly spaced relation with the tooth which would be engaged therewith if by any chance the ratchet were to be torsionally stressed in a reverse direction. However, it may be observed that there is no normal stress in that direction, the pressure of the spring 44 continually frictionally engaging said sleeve 22 which carries the ratchet wheel 21 so that relative turning movement of said ratchet wheel 21 and the pawl carrier head 16 is thus continually frictionally opposed.

Fig. VIII shows a modified form of my invention differing from that of Fig. VII only in the substitution of the keeper pawl 45'' for the keeper pawl 45' of Fig. VII; said keeper pawl 45'' having its edge which cooperates with the teeth of 65 the ratchet wheel 21 parallel with the axis of rotation of said ratchet wheel so as to oppose only a corner of the tooth which said keeper pawl would engage if the ratchet wheel were stressed to turn backward. However, in view of the frictional stress of the spring 44 which holds the ratchet wheel 21 in any position to which it is advanced by the advancing pawl 17, it is in fact unnecessary to provide any keeper pawl.

It may be observed that in each of the several 75

forms of my invention above described, a single pawl, to wit, the pawl 17, is utilized to advance the ratchet 21 under the actuation of both the whole cents computing mechanism and the fractional cents computing mechanism.

Therefore, I do not desire to limit myself to the precise details of construction and arrangement herein set forth, as it is obvious that various modifications may be made therein without departing from the essential features of my invention, as defined in the appended claims.

I claim:

1. In a mechanical movement embodying compound variable drive mechanisms; a ratchet wheel; and means for imparting to said ratchet wheel rotary movement, including a rotary pawl carrier and an advancing pawl on said carrier for engaging the teeth on said ratchet; and means for preventing accidental rotary displacement of said ratchet wheel, including a keeper pawl for engaging the teeth of said ratchet; wherein both the ratchet wheel and the keeper pawl are mounted for axial movement relatively to the pawl carrier, and including a slide bearing supported by said pawl carrier, and engaging both said keeper pawl and ratchet, and means for effecting relative axial movement of said wheel and pawl, whereby axial movement of the ratchet is imparted to said bearing and keeper pawl.

2. Mechanism as in claim 1, wherein the teeth on the ratchet wheel are helically inclined with respect to the axis of its rotation.

3. Mechanism as in claim 1, wherein the edge of the advancing pawl engaging the teeth on the ratchet wheel is helically inclined with respect to the axis of said wheel.

4. Mechanism as in claim 1, wherein the teeth

on the ratchet wheel are helically inclined with respect to the axis of its rotation and the edge of the advancing pawl is similarly inclined.

5. Mechanism as in claim 1, wherein the teeth on the ratchet wheel are helically inclined with respect to the axis of its rotation and the edges of both the advancing pawl and keeper pawl engaging said teeth are similarly inclined.

6. In a mechanical movement embodying compound variable drive mechanisms; gear pinions of the respective mechanisms in coaxial relation; means preventing relative axial movement of said gear pinions; a shaft extending in coaxial relation with both of said pinions and rigidly connected with one of them and rotatable independently of the other of said pinions; a ratchet wheel mounted to reciprocate axially on said shaft; means preventing relative rotary movement of said shaft and ratchet wheel; a rotary pawl carrier rigidly connected with said pinion which is independent of said shaft; respective advancing and keeper pawls carried by said pawl carrier for engagement with the teeth of said ratchet wheel; and means for reciprocating said ratchet wheel independently of said pinion with which it is connected; whereby said ratchet wheel is advanced relatively to said other pinion.

7. Mechanism as in claim 6, including means axially movable with said ratchet wheel for axially moving said keeper pawl with respect to said pawl carrier.

8. Mechanism as in claim 6, wherein the teeth of the ratchet wheel are helically inclined with respect to its axis of rotation and the edges of the pawls for engagement with said ratchet wheel are similarly inclined.

VICTOR H. RAUSCH.
